(57) **CLAIM**

The ornamental design for a lighting fixture, as shown and described.

DESCRIPTION

FIG. 1 is an enlarged fragmentary end view of the lighting fixture, slightly tilted and showing one end and a portion of the bottom, of the new design;

FIG. 2 is a fragmentary perspective view showing one end, a portion of one side, and a portion of the bottom thereof; and,

FIG. 3 is a longitudinal side elevation thereof.

1 Claim, 2 Drawing Sheets

FIG. 1**FIG. 2**

FIG. 3
